Attorney.*

UNITED STATES PATENT OFFICE.

WILLIAM H. HOLLAR, JR., OF DREXEL HILL, AND WALTER G. UHLMAN, OF PHILADELPHIA, PENNSYLVANIA.

KEY ENVELOPE.

Application filed December 16, 1926. Serial No. 155,222.

It is the present practice for banking institutions to lease what are termed "deposit boxes", to wit, small drawers provided with locks, which may be opened by keys furnished to the lessees. Despite the usual precautions, it is possible that such boxes may be fraudulently opened by any employee of the lessor who has had access to the keys before delivery of the same to the lessee, and 10 thus had an opportunity of making, or having made, a duplicate or duplicates of the same.

Therefore, the principal object and effect of our invention is to provide an envelope 15 with means so constructed and arranged that it may be utilized to seclude any such original key, from the time of its manufacture until its delivery to the lessee.

It is the usual practice, and is desirable, 20 to store such keys in racks comprising compartments but slightly larger than the shanks of two similar keys which are furnished with each lock for the use of the lessee. Therefore, it is a further object and 25 effect of our invention to provide an envelope which may be used to seclude such a pair of keys together and in such manner as not to interfere with the storage and removal of such key packages with respect to such 30 racks.

In the form of our invention hereinafter described, such an envelope includes a sheet of flexible material which may be wrapped around the shank portions of the keys which 35 are provided with the biting notches for the lock tumblers. Said sheet is provided with two narrow flexible connecting members preferably formed in unitary relation therewith and extending in alinement from respectively opposite ends thereof, one of 40 which may be extended through a hole in the handle of a key and have its end returned parallel with the other connecting member so that the ends of said connecting members 45 may be sealed together, to prevent access to the key except by disruption of said seal. Such sealing may be effected by spot welding or riveting the two connector ends together, as hereinafter described.

50 Although such sealing means is in no sense "burglar proof", it is of such character as to manifest if any attempt has been made to open it, and the fact that it has not been tampered with, affords assurance to the lessee that no unauthorized person has had an

opportunity of making a duplicate of the key or keys thus secluded.

Our invention includes the various novel features of construction and arrangement hereinafter more definitely specified. 60

In said drawings: Fig. I is a perspective view of an envelope embodying our invention, in its initial form and condition, before use. 65

Fig. II is a perspective view of the envelope of Fig. I, secluding two keys, and in its normal sealed condition. 65

Fig. III is a longitudinal sectional view of the structure shown in Fig. II.

Fig. IV is a transverse sectional view of 70 said structure, shown in Figs. II and III.

Fig. V is a perspective view of a modified form of envelope, wherein the flexible connectors are formed of a piece of metal which was primarily separate from the envelope. 75

Fig. VI is a perspective view of a modified form of envelope, wherein the flexible connectors are formed of a single piece of wire. 80

Fig. VII is a perspective view of the envelope of Fig. VI, secluding two keys and in its normal sealed condition. 85

Referring to the form of our invention shown in Figs. I to IV inclusive; the envelope 1 is conveniently formed of a primarily plane sheet of ductile metal, such as brass or copper; the rectangular body thereof having opposite end edges 2 and 3 and side edges 4 and 5. Said envelope 1 has connectors 7 and 8 projecting from the respectively opposite ends of said body at its edges 2 and 3, in alinement with said edge 5 and in unitary relation with said body. 90

Said envelope may be bent upon the four lines 10, 11, 12, and 13, indicated by dots in Fig. I, to the tubular form shown in Fig. 95 IV; wherein the edge 5 overlaps the edge 4. Said tube is adapted to receive and seclude the shanks 14 of duplicate keys provided with the bitings 15, and said connector 7 is extended through the registered holes 16 in the bow handles 17 of said keys, and the end of said connector returned parallel with said edge 5 of the envelope body but upon the opposite side of the package so as to present its end parallel with the end of the connector 8. 100 Said connectors may then be sealed together by any suitable means, for instance, by a tubular eyelet 19 extending through them and clinched upon opposite sides thereof. 105

Said key shanks 14 are thus secluded so 110

that neither of them, nor the bittings 15 thereof, can be copied upon another key blank without opening said envelope 1; by 5 breaking either of said connectors 7 or 8 or disrupting said sealing means. Consequently any attempt to use said keys in any 10 fraudulent manner above contemplated, is manifested by the damaged condition of their inclosure, and, if the envelope and seal 15 are intact when delivered to the lessee, the latter is assured that no unauthorized person has had the opportunity of making a 20 duplicate of the keys thus secluded. However, said connectors 7 and 8 may be easily cut 25 to release said keys for legitimate use.

The form of our invention shown in Fig. V differs from that shown in Fig. I, in that the flexible connectors 21 and 22 are formed 20 of a single strip of metal which is primarily 25 separate from the envelope body 23 but is connected therewith by extending it under the folded edge flap 24 of said body. The advantage of such construction is that it avoids waste in cutting the sheet material 30 which is unavoidable in the production of envelopes in the form shown in Fig. I, wherein the connectors 7 and 8 are in unitary 35 relation with the envelope body 1. The envelope shown in Fig. V may be employed to 40 inclose and seclude a pair of keys in substantially the same manner as indicated in Figs. II to IV inclusive.

Fig. VI shows a modified form of our invention wherein the flexible connectors 25 35 and 26 are formed of a single piece of wire which is connected with the envelope body 27 by extending it under the folded edge flap 28 of said body 27. Of course, the small cylindrical connectors 25 and 26 are 40 not adapted to be connected by the rivet means shown in Figs. II and III. The envelope structure of Fig. VI may be used to 45 seclude a pair of keys in substantially the same manner as shown in Figs. II to IV inclusive and as indicated in Fig. VII, and 50 said connectors 25 and 26 be sealed together by spot welding them at 30. However, for the purpose of utilizing the key racks aforesaid, any suitable sealing means may be 55 employed, for the envelopes above contemplated, provided that it does not project beyond the cross sectional dimensions of the package, and consequently extends within the longitudinally extending boundary planes of the package, as shown, for instance, in Figs. II, III and VII.

Therefore, we do not desire to limit ourselves to the precise details of construction and arrangement herein set forth, as it is obvious that various modifications may be 60 made therein without departing from the essential features of our invention, as defined in the appended claims.

We claim:

1. The combination with an envelope 65 formed of flexible sheet metal, adapted to be wrapped around a key and having two connector members in integral relation therewith, one of said members being adapted to extend through a hole in said key and into proximity to the other connector; of sealing means, connecting said connectors, independently of the body of said envelope; whereby a key may be secluded in said envelope until the latter is disrupted or said sealing means 70 displaced.

2. The combination with an envelope 75 formed of flexible sheet metal, adapted to be wrapped around a key and having two connector members in integral relation therewith, one of said members being adapted to extend through a hole in said key and into proximity to the other connector; of sealing means, including a tubular rivet, connecting 80 said connectors, independently of the body 85 of said envelope; whereby a key may be secluded in said envelope until the latter is disrupted or said sealing means displaced.

3. An envelope formed of a primarily flat sheet of flexible material adapted to be 90 wrapped around the shank of a key having a handle larger than said shank, and having two connector members, in unitary relation therewith, adapted to extend in proximate 95 relation at one end of said key; and sealing means connecting said connectors; said sealing means and the portions of the connectors adjacent thereto being within the longitudinally extending boundary planes of the package; whereby the package is adapted to 100 removably fit in a rack opening smaller than said handle and snugly fitting the perimeter of said package immediately adjoining said handle, and said key may be secluded in said envelope until the latter is disrupted or said sealing means displaced.

In testimony whereof, we have hereunto signed our names at Philadelphia, Pennsylvania, this 30th day of November, 1926.

WILLIAM H. HOLLAR, JR.
WALTER G. UHLMAN.
